[57] CLAIM

The ornamental design for a road wheel tire, as shown
and described.

DESCRIPTION

FIG. 1 is a perspective view of a road wheel tire showing
my new design it being understood that the tread
pattern is repeated uniformly throughout the circumference
of the tire and the opposite side is the same as that
shown;

FIG. 2 is a right side elevational view thereof;
FIG. 3 is a front elevational view thereof; and
FIG. 4 is a longitudinal sectional view thereof taken
along line 4—4 in FIG. 3.

FIG. 4

FIG. 1

FIG. 3

FIG. 2
